SHARPENING DEVICE

John Holtzman, New York, N. Y., assignor of one-half to Irving F. Goodfriend, New York, N. Y.

Application May 16, 1942, Serial No. 443,273

4 Claims. (Cl. 120—90)

This invention relates to a sharpening device for a tailor's crayon or chalk.

My invention contemplates the provision of a device by means of which the crayon or chalk, such as that used by cloth cutters and tailors to mark the fabric or cloth upon which they operate, may be sharpened to provide the fine knife-like edge required in such work.

Due to the composition of the crayon or chalk, when the edge thereof is shaved and thereby sharpened, the particles of shavings have a tendency to pack and adhere to the cutting means such as that heretofore used, necessitating frequent cleaning by the tailor or cutter. My invention contemplates the provision of a sharpening device, for such crayon or chalk which is self-cleaning and which may be so arranged so that the shavings may be accumulated in the means supporting or carrying the sharpening members for later disposal therefrom.

My invention still further contemplates the arrangement of such a shaving device having a sharpening means and as a plane-like knife edge, arranged and constructed so that it will not become clogged and thereby rendered inoperative to form on the crayon or chalk the sought for knife-like marking edge.

Other objects and advantages of my invention will be clear from the description which follows and the drawing relating thereto, in which:

Fig. 1 is a top plan view of a sharpening device according to my invention.

Fig. 2 is a section on the line 2—2 of Fig. 1.

Fig. 3 is a section on the line 3—3 of Fig. 2.

Fig. 4 is a side elevation of the sharpening member assembly, removed from the carrying tray.

Fig. 5 is a perspective view of a conventional crayon or chalk, which may be sharpened with a device according to my invention.

Referring now to the drawing and particularly to Figs. 1 to 4 inclusive, the cutter or sharpening member assembly 10 may be removably carried in the bed 12, the frame end walls 13 and side walls 15, of which extend up from the bottom 14 of the tray 16 in the center thereof and in which bed the assembly 10 fits relatively snugly.

The assembly 10 comprises two similar members for carrying the plane-like knives 18, which extend through the slots 20 arranged in the upper inclined portions 22, extending upwardly from the straight lower portion 24 of the assembly member.

The preferably straight lower portion 24 of the similar members may be secured together by any suitable means, such as rivets or the screws 26 to form the assembly base which is snugly carried in the bed 12.

The upper portions 22 diverge away from each other to form a V-shaped in cross section, guideway, groove or trough 28 in which the crayon or chalk 30 is moved to shave therein the desired marking edge 32.

The conventional tailor's chalk or crayon 30 (Fig. 5) is customarily formed of a relatively oblong rectangular plate, the elongated marking edges 32 of which have been sharpened into an acute angle, V-shaped in cross section.

The cutting edges 34 of the knives 18 extend through the slots 20 beyond the inner surfaces of the inclined upper portions 22 into the guideway or groove 28, a distance sufficient to shave or sharpen the edge 32 into the angular cross section sought or selected.

The knives 18 are secured for removal therefrom, in the event it is desired to sharpen the cutting edges thereof, to the upper inclined portions 22 by any suitable means, preferably for selective positioning in the device, as by the screw 36, the threads of which engage the correspondingly threaded groove 38. In order to permit the cutting edge 34 to be selectively positioned in the guideway or groove 28, preferably I provide the elongated slot 40 in the body of the knife 18, in which slot the screw 36 passes to enable the knife to be secured on the portion 22 in the desired position.

In order to define the entrance 42 to the guideway or groove 28 so that the crayon or chalk 30 will be advanced therein in the proper direction against the cutting edges 34, I preferably cut away the upper portions 22 adjacent the entrance thereto as indicated at 42. This cutaway part preferably terminates just in advance of the slot 20 and cutting edge 34 and additionally serves to somewhat relieve any resistance, frictional or otherwise, to the passage of the crayon or chalk along the guideway or groove, since the knives, by reason of this, begin to shave the crayon or chalk almost immediately upon its entrance into that part of the guideway which is surrounded by the walls forming it.

As the crayon or chalk 30 is moved through the guideway or groove 28, the cutting edges 34 of the plane-like knives 18 bite into it to shave off the edges thereof. Since the guideway or groove is V-shaped in cross section and the cutting edges of the sharpening means there-

by correspondingly inclined, an angular knife-like marking edge is formed on the crayon or chalk.

The cuttings or shavings are directed by the preferably beveled knife edge 34 through the slot 20 to accumulate on each side of the cutter assembly bed 12 in the interior or chamber 44, formed by the upstanding end walls 46 and side walls 48 of the tray 16. It will be apparent that by reason of this construction just described, the sharpening device is substantially self-cleaning, since the shavings or cuttings will necessarily fall through the slots away from the cutting edges and provision being made for the accumulation of the cuttings or shavings, as they are made, in a tray or support in which the sharpening member is carried.

Since the cutter assembly 10 is snugly but removably carried in the bed 12 of the tray 16, it will be recognized that the sharpening device may be used as a separate implement, if so desired.

While I have illustrated and described a certain embodiment of my invention, I do not intend to be limited to the specific details of construction shown, but intend to claim my invention as broadly as the prior art and the scope of the appended claims permit.

I claim:

1. In a sharpening device for a tailor's crayon or chalk of a relatively oblong shape and having an elongated beveled V-shaped in cross-section marking edge; a tray for catching and accumulating therein shavings from the crayon as it is sharpened by the device, spaced walls extending up from the bottom of the tray to form a bed for detachably carrying a crayon or chalk sharpener in position in the tray; and a crayon or chalk sharpener comprising two similar members, each member having a lower portion and an upper portion extending therefrom at an angle thereto, said lower portions secured together to form a base corresponding in shape to the bed to be snugly fitted therein, said upper portions forming a V-shaped guideway for moving the crayon or chalk therethrough to sharpen a V-shaped edge thereon, said upper portions each having an opening therein and a boss for carrying a sharpener blade extending therefrom on each upper portion at the rear of the opening on the outside of the guideway and at an angle to the lower portion corresponding to that of the upper portion to said lower portion, said boss having a surface inclined toward the guideway from the rear of the boss to the rear edge of the opening, sharpener blades each having a beveled cutting edge and an elongated slot, and threaded means extending through the slot for securing a blade on the surface of a said boss with the blade cutting edge positioned in the guideway at the rear edge of the opening and the bevel of the cutting edge inclined away from the guideway toward the rear thereof.

2. In a sharpening device for a tailor's crayon or chalk of a relatively oblong shape and having a beveled V-shaped marking edge comprising two similar members, each member having a lower portion and an upper portion extending

therefrom at an angle thereto, said lower portion secured together to form a supporting base, said upper portions forming a V-shaped guideway for moving the crayon or chalk therethrough to sharpen a V-shaped edge thereon,

5 said upper portions each having an opening therein and a boss for carrying a sharpener blade extending therefrom on each upper portion at the rear of the opening on the outside of the guideway and at an angle to the lower portion corresponding to that of the upper portion to said lower portion, said boss having a surface inclined toward the guideway from the rear of the boss to the rear edge of the opening; sharpener blades each having a beveled cutting edge and an elongated slot, and threaded means extending through the slot for securing a blade on the surface of a said boss with the blade cutting edge positioned in the guideway at the rear edge of the opening and the bevel of the cutting edge inclined away from the guideway toward the rear thereof.

3. In a sharpening device for a tailor's marking crayon or chalk of relatively oblong shape and having a beveled V shaped in cross section marking edge, comprising two similar members, each member having a lower portion and an upper portion extending therefrom at an angle thereto, said lower portions secured together to

25 constitute a supporting base, said upper portions forming a substantially V shaped in cross section guideway for moving a crayon or chalk therethrough to sharpen a V shaped in cross section marking edge thereon, each of said upper portions having an opening therein, a boss for carrying a sharpener blade extending therefrom on each upper portion at the rear of the opening on the outside of the guideway and having an inclined surface from the rear of the boss to the rear edge of the opening and a sharpener blade secured to the inclined surface of each boss with the cutting edge extending through the opening into the guideway at the rear of the opening and the bevel of the cutting edge inclined away from the guideway toward the rear thereof.

4. In a sharpening device for a tailor's marking crayon or chalk of a relatively oblong shape and having a substantially V-shaped in cross section marking edge, comprising two similar members each member having a lower portion and an upper portion extending therefrom at an angle thereto, threaded means securing said lower portions together to form a supporting base,

30 said upper portions constituting a V-shaped guideway for moving a crayon or chalk therethrough to sharpen a V-shaped marking edge thereon, each of said upper portions having an opening therein, a support for carrying thereon a sharpener blade, said support extending from the opening on each upper portion at the rear of the opening on the outside of the guideway at an angle thereto from the rear of the support to the rear edge of the opening and a sharpener blade secured to the boss with the cutting edge extending through the opening into the guideway at the rear of the opening.

JOHN HOLTZMAN.
